UNITED STATES PATENT OFFICE.

JOHN M. FAILEY, OF AKRON, OHIO, ASSIGNOR TO THE B. F. GOODRICH COMPANY, OF NEW YORK, N. Y., A CORPORATION OF NEW YORK.

STRAP FASTENING.

1,408,281.

Specification of Letters Patent. Patented Feb. 28, 1922.

Application filed September 30, 1919. Serial No. 327,499.

To all whom it may concern:

Be it known that I, JOHN M. FAILEY, a citizen of the United States, residing at Akron, in the county of Summit and State 5 of Ohio, have invented a certain new and useful Strap Fastening, of which the following is a specification.

My invention relates to strap and buckle fastenings wherein a strap end runs through 10 a buckle having a suitable gripping member.

My object is to provide such a construction of the strap that the buckle will securely engage the same without slipping and may easily be released when desired.

15 Of the accompanying drawings—

Fig. 1 is a perspective view of an apparel belt embodying my invention and having an automatic buckle for connecting the ends.

Fig. 2 is a longitudinal sectional view 20 through a portion of the apparel belt or other strap fastening, showing the buckle and the strap or belt ends.

In the drawings, the tongue end 10 of a belt 11 is connected with the other belt end 25 12 by an automatic buckle 13 which is shown as having a cylindrical belt-clamping bar 14 freely movable in a pair of cam slots 15 diagonally toward and from the inner surface 16 of the belt, whereby, when the bar is 30 moved against the belt, the tension of the latter causes the bar to be wedged thereagainst.

In Fig. 2 I have shown a preferred construction in which the belt is formed of a 35 plurality of layers or laminations, herein three, designated by the numerals 18, 19 and 20, the inner and outer layers 18 and 20 consisting preferably of a vulcanized compound of rubber and unorganized cotton fibres, such 40 as is commonly used as a leather substitute, while the intermediate layer 19 (located nearer to the inner than to the outer surface of the belt, as shown) consists of a strip of straight-laid rubberized fabric vulcanized 45 to the two adjacent layers.

To prevent slippage of the buckle bar 14, the inner surface of the belt is permanently roughed, as by molding transverse corrugations 17 therein, beginning in the case of the 50 apparel belt at a point adjacent the extrem-

ity of the tongue end and extending longitudinally of said tongue end for several inches to allow for any adjustment of the buckle relative to the strap end. These corrugations are relatively shallow and closely 55 spaced, so that the buckle bar will not become wedged into a recess of the corrugated surface, the bar preferably engaging and slightly compressing two or more of the projections of the corrugated surface and being 60 held against these projections by the wedging action of the bar in the cam slots. While the corrugations prevent slipping of the bar and a resultant loosening of the belt, the bar may easily be released by pulling back simultaneously 65 on its two projecting ends, or by first drawing on the tongue end of the belt while holding the buckle, as in tightening the belt, which will release the clamping bar and allow it to be retracted. Corrugations 70 formed on the inner surface of this form of belt will not be worn smooth or pressed down as soon as corrugations formed on a leather or other belt, for the admixture of the cotton or other fibre in the rubber increases its toughness 75 and resistance to compression without materially reducing the tendency of the rubber to resume its normal shape after the pressure thereon, such as caused by the bar, is released. The remainder of the inner surface of the 80 belt is smooth, permitting a sliding of the belt on a garment when adjusting its position on the latter.

I claim:

1. In an apparel belt, the combination of a 85 strap having a smooth surface extending around its inner circumference to the belt tongue, permitting a sliding of the belt on a garment, and having a tongue end permanently formed with a roughened inner surface, and a buckle having a clamping member adapted to engage and compress said roughened surface.

2. In an apparel belt, the combination of a 90 rubber composition strap having a substantially smooth inner surface from its buckle end to its tongue end and having slightly- 95 resilient transverse corrugations permanently formed on the inner surface of the tongue end, and a buckle having a gripping 100

member adapted to compress the corrugations on the tongue end when the belt is under tension.

3. An apparel belt comprising a rubber composition strap having an inner surface permanently formed with slightly compressible projections adjacent the tongue end of the belt, and a buckle on the opposite end

of the belt having a diagonally-movable, rotatable gripping bar adapted to wedge 10 against a plurality of the transverse ridges of the corrugated surface of the strap.

In testimony whereof I have hereunto set my hand this 24th day of September, 1919.

JOHN M. FAILEY.
